UNITED STATES PATENT OFFICE.

LINN BOYD BENTON AND MORRIS FULLER BENTON, OF PLAINFIELD, NEW JERSEY,
ASSIGNORS TO AMERICAN TYPE FOUNDERS COMPANY, OF JERSEY CITY, NEW
JERSEY, A CORPORATION OF NEW JERSEY.

FONTING APPARATUS.

1,418,057.

Specification of Letters Patent. Patented May 30, 1922.

Application filed June 9, 1921. Serial No. 476,170.

To all whom it may concern:

Be it known that we, LINN BOYD BENTON and MORRIS FULLER BENTON, both citizens of the United States, and both residents of 5 Plainfield, county of Union, and State of New Jersey, have invented a certain new and useful Fonting Apparatus, of which the following is a specification.

The invention relates to apparatus for 10 fonting and distributing type, and more particularly to the fonting of the special form of type employed in connection with composition and printing machines of the "multigraph" type, and is illustrated and described 15 herein in connection with the particular form of type used in such machines, but it is to be understood that the invention may be carried out in connection with other forms of type, or with bodies other than type and 20 which may be arranged in groups.

The objects of the invention are to provide an apparatus of the character described in which type may be transferred from one 25 tubular magazine to another expeditiously and with certainty, and without injury to the type; which will be positive in its action; which will be of strong and rigid construction; which will be cheap to construct and which will not require skilled labor to 30 operate.

These and further objects will more fully appear in the following specification and accompanying drawings considered together or separately.

35 One embodiment of the invention is illustrated in the accompanying drawings, in which like parts in all of the several figures are designated by similar characters of reference, and in which—

40 Fig. 1 is a side elevation of an apparatus embodying the invention.

Fig. 2 is a fragmentary end elevation taken from the inlet-end.

Fig. 3 is a detail plan view, on an enlarged 45 scale, illustrating the transfer point.

Fig. 4 is a detail section taken on the line 4—4 of Fig. 3.

Fig. 5 is a detail section taken on the line 5—5 of Fig. 4.

50 Fig. 6 is a rear elevation of the apparatus.

Fig. 7 is a detail section on an enlarged scale of a magazine clamping device.

Fig. 8 is a fragmentary top plan view of a filled magazine.

55 Fig. 9 is a side elevation of the same.

Fig. 10 is a rear elevation of the same.

Fig. 11 is a front elevation of the same, and

Fig. 12 is a detail elevation of the operating mechanism, showing the same at the beginning of a feed movement.

The type employed in multigraph and other special forms of composing, printing and distributing machines, are of special shape, having short bodies *a* and with oppositely disposed notches *b* in the bodies. The type are fed into a tubular magazine *c* provided with a longitudinal slot *d* extending from end to end thereof as shown in Fig. 8. One end of the tube is flared as at *e* whereby the mouth of the slot *d* is enlarged to provide for the ready entrance of the type which are moved into the tube with the edges of the slot engaging the notches *b* whereby the type will be suspended with the face end 65 projecting outside of the tube and with the foot disposed inside of the tube, as shown in Fig. 11.

The opposite end of the slot is closed by bending the edges downward and inward, as shown in Fig. 8 and whereby the type cannot be removed from the tube through that end of the tube. When the tube has received the desired number of type, which will be somewhat less than is required to fill it, a 70 spring clip *f* is placed in position over the tube, as shown in Figs. 8, 9 and 11 whereby the type are securely positioned between the closed end of the slot and the clip.

75 The apparatus of the present invention is for the purpose of fonting the type after they have been delivered from the casting machine.

80 The apparatus comprises a pair of opposed frame members 1 and 1^a, provided with feet 2 by means of which the device may be secured in position, and secured in opposed relation by means of stay bars 3, 4 and 5. A shaft 6 is journaled in the members 1 and 1^a and projects beyond the 85 former, for the purpose to be hereinafter described.

85 Diametrically opposite the stay bar 3 is a guide rod 7 which extends between the frame members 1 and 1^a and is secured thereto.

90 Secured to the shaft 6 in proximity to the frame member 1 is a disc 8 provided with a circular series of semi-circular notches 9 axially arranged on the periphery thereof. Radially arranged relatively to the 95

notches 9 is a series of spring pressed rods 10 extending through the disc 8, and carried on the outer end of each rod 10 is a block 11 which extends radially outward in alignment with a notch 9. Carried by the block and extending into the notch is a conical pointed pin 12. A guide pin 13 carried by the block extends through a perforation in the disc 8 as shown in Fig. 7. The disc 8 is positioned at a distance inside of the frame member 1 whereby there will be a considerable space between the said member and the blocks 11.

Rigidly secured to the shaft 6 in proximity to the frame member 1^a is a disc 14 having a series of notches 15 in its periphery. The notches 15 correspond in number and position with the notches 9. Resting in each notch 15 is a saddle block 16 having a working fit in the notch. Each saddle block is provided on its outer face, which is normally flush with the periphery of the disc 14, with a semi-cylindrical groove 17 extending longitudinally across the same. A spring 19 seated in a radial opening in the disc 14 tends to move the saddle block radially outward. A screw 18 carried in the inner face of the disc 14 has its head bearing against the inner end of the block 16. One side of the head of the screw is removed whereby the blocks may be positioned in the disc.

Secured to the disc 14, and between the same and the frame member 1^a is an annulus 20 the outside diameter of which is somewhat greater than that of the disc 14. The annulus 20 is provided with a series (corresponding in number and position to the notches 9 and 15) of perforations 21 which taper slightly from the inner to the outer side of the annulus. The perforations 21 are arranged a short distance within the periphery of the annulus, and an axial slot 22 is formed in the periphery in radial alignment with the center of each perforation. Between each pair of slots 22 a lip 23 projects axially inwardly. Each lip projects over an edge of two saddle blocks, the spaces between the lips forming slots one over the center of each saddle groove 17. The sides 50 of the lips are inclined whereby the slots are gradually widened toward the ends of the lips. The under side of each lip adjacent to the edge thereof is rounded with a radius corresponding to that of the saddle groove 17, as shown in Fig. 5. The periphery of the ring 20 as a whole including the lips 23, is tapered slightly from the outside next to the frame member 1^a, inwardly, as shown in Fig. 4 for a purpose to be herein-60 after described.

The frame member 1^a is provided with a gate, preferably near the top thereof. Said gate comprises a perforation 24 similar to 21 but tapered in the opposite direction. A slot 25 similar to the slots 22 is formed in

the gate, and a lip 26 similar to the lips 23 is positioned at each side of the gateway. A saddle block 27 similar in all respects to the saddle blocks 16 is positioned in alignment with the perforation 24. The side of the annulus 20 is in close proximity to the inner side of the frame member 1^a, and the inner side of the block, in which the gate is formed, to one side of the slot 25 is inclined at 28 as shown in Figs. 3 and 4.

Extending outward from the frame member 1^a and parallel to the axis of the perforation 24 is a guide rod 29, and sliding on the rod is a head 30 which may be secured in desired position longitudinally of the rod by means of a thumb screw 31. The head carries a spring actuated block 32 carrying a clamping pin 33. The device carried by the head 30 is similar in all respects to the spring actuated elements carried by the disc 8.

Rigidly mounted on the shaft 6, and midway between the discs 8 and 14 is an alining disc 34 for a purpose to be hereinafter described.

The tie rod 3 is mounted in ears 35 and 35^a offset from the frames 1 and 1^a respectively as shown, and a hub 36 provided with a set screw 27 is slidably mounted on the rod. A gauge ring 38 is rigidly secured to the hub 36, and the ring, at a point diametrically opposite the rod 3, is provided with a perforation through which the guide rod 7 passes with a loose fit.

Pivoted to the ear 35 is a weighted stop-lever 39 having a projecting foot 40. The stop lever is pivoted to the ear above the rod 3 and the foot normally rests against the side of the rod 3 and in the path of the hub 36. The foot 40 is of such a length that the hub will contact with it at a considerable distance from the ear whereby when the lever is swung away from the rod by means of its handle the hub may have additional movement to the left in Fig. 1 whereby the gauge ring will clear the disc 8.

Rigidly secured to the shaft 6 outside of the frame 1 is an index wheel 41 having spaced notches 42 in its periphery. The notches correspond in number to the notches 9 and 15, and the perforations 21. A hand wheel 43 is rigidly secured to the shaft 6 outside of the index wheel 41 whereby the index wheel and discs 8 and 14 may be manually operated when desired.

Pivoted on the shaft 6 between the index wheel and the frame is an operating lever 44 carrying a handle 45 at one end and attached by means of a spring 46 to the frame 1 at its opposite end.

Pivoted to the lever 44 near the handle end thereof is a spring pressed pawl 47 having a tooth 48 for engagement with the notches in the index wheel. The tooth 48 has its sides formed to accurately engage the sides of the notches 42.

Pivoted to the frame 1 is a locking dog 49 which is normally held in engagement with the index wheel by means of a light spring 50. The tooth of the dog is of a size 5 and shape to accurately fit a notch in the wheel. The dog is provided with a beveled toe 52 adapted to engage against the beveled side of a spring actuated block 53 carried by lever 44. A cam 54 pivoted to the frame 1 is adapted to engage the tail of the dog to move the tooth thereof out of engagement with the index wheel when it is desired to manually rotate the latter.

When the cam 54 is moved to engage the tail of the dog 49, a pin 49^a carried by the dog, will engage the pawl 47 and lift the tooth thereof from engagement with the index wheel. The shaft 6 and the elements carried thereby will now be free to be rotated in either direction by means of the hand-wheel 43.

It will be understood that the lever 44 may be vertically arranged with the handle 45 extending upward, in which case the spring 50 and the pawl spring may be omitted, and the pawl and dog will engage the index wheel by gravity.

The operation of the apparatus is as follows:

30 The lever 39 is swung away from the rod 3 and the gauge ring is moved to the left, in Fig. 1, until it clears the disc 8, and the dog 49, and pawl 47 are lifted out of engagement with the index wheel by means of the cam 54. A slotted tube, such as the tube *c* above described, is now placed in the alined notches 9 and 15 in the following manner:

35 The closed end of the tube is passed over a pin 12 and the block 11 is pressed back against the tension of its spring until the open end of the tube clears the inner ends of the lips 23. The open end of the tube is now placed in the groove of the alined saddle block 16 and the latter forced inward 40 against the tension of its spring 19 to the position shown at *w* in Fig. 5. The tube is now moved to the right beneath the overhanging lips 23 on either side of the saddle block with the slot *d* of the tube in alinement with the slot 22.

45 The lips 23 and 26 are of gradually increasing thickness of metal over the tube and the latter will be firmly held against a strong and rigid rim by the spring 19. The notches in the type bodies are of sufficient width to permit of the type being raised as they enter the slots between lips 26 and passing over the adjoining portions of the block and the annulus 20. The taper of the lips 50 23 will permit the type to be gently lowered to engage the tubes carried by the discs 8 and 14.

The shaft 6 carrying the discs 8 and 14 is now rotated the distance of one notch of 55 the index wheel and another tube is placed

in position, and the operation is repeated until the desired number of tubes are in place.

The cam 54 is now turned to release the dog, and the latter in engaging a tooth in 70 the index wheel will lock the shaft 6 in position with a tube *c* in alinement with the gate in the frame 1^a.

Each tube *c* will be supported at its center and held in alinement by engagement 75 with the alining disc 34. The bore of the gauge ring is of such a diameter that it will clear the outer sides of the tubes, and thereby prevent wear on the gauge ring.

The apparatus is now in position to receive type as they are received from the casting machine. When the type are fed out of the casting machine they are moved into a tube similar to the tube *c* except that both ends of the tube are open and the slot is of 80 the same width throughout. Before the type are placed in the tube, a clip similar to *f* is placed over the same, and when the tube is nearly full a similar clip is placed over the opposite end to retain the type in place 85 during transportation.

A tube loaded with type bearing the same character, as loaded in the casting machine, and with the spring clips removed, is 90 now placed with one end in the gate and with its opposite end supported by the head 30 in the same manner as that above described in connection with the receiving tubes. The loading tube will now be in 95 axial alinement with one of the receiving 100 tubes of the circular series.

The first loading tube will contain A's and 105 may be of any length desired, it being understood that while the receiving tubes are limited in length by the distance between the frames of the apparatus, the casting machine tubes are not so limited but may be of any desired length, the adjustability of the head 30 toward or away from the frame providing for the employment of tubes of 110 various lengths.

Assuming that the font desired is one containing five A's, four B's, six C's, and the proper number of other letters, figures, and punctuation marks, the operator will proceed as follows:

115 She will count off five type from the open end of the loading tube, and by means of a sharp edged tool, separate the group of five from the rest of the type in the delivery tube and move them to the left into the alined receiving tube, it being understood that the lever 44, pawl 47 and dog 49 are in the positions shown in Fig. 6 with the dog locked between the block 53 and a notch in 120 the index wheel 41 whereby the latter is positively locked against rotation. The pawl 47 at this time is loosely engaging the index wheel and has no effect on the locking 125 of the wheel.

The handle 45 is now depressed bringing the pawl down to engage the next notch in the index wheel. This movement will release the spring block 53 from behind the dog, but the latter will be retained in engagement with the notch of the index wheel by means of the spring 50, and will prevent the wheel from following the pawl.

The downward movement of the lever 44 10 is limited by a stop 44^a. The stop is so positioned that the lever cannot be depressed a distance sufficient to permit the pawl to take up two teeth, and as the dog and pawl are 15 engaging the same notch when the dog is in locked position, the indexing will be accurate whether the notches 42 are equally spaced or not. The handle is now released and the spring 46 will raise the pawl and 20 rotate the index wheel in the anti clockwise direction as viewed from the operating end of the apparatus as shown in Fig. 6.

The rotation of the index wheel under the influence of the spring 46 will disengage the dog from the wheel and move it back against 25 the tension of the spring 50. As the handle end of the lever 44 ascends the top of the trigger block 53 will engage beneath the leg 51 of the dog. The continued upward movement of the lever will cause the block to be 30 depressed against its spring, and when the tooth of the dog is opposite a notch in the index wheel the spring 50 will throw the dog into the notch. When the dog starts on its inward movement the point of its tooth 35 is not in position to engage the bottom of the notch as the latter is a short distance back of its ultimate position. The point of the tooth will enter the notch, engage the upper wall of the notch and the continued upward 40 movement of the handle will continue to depress the trigger 53 until the trigger slips from beneath the leg 51, when the inclined face of the trigger will engage the inclined 45 end of the toe 52, and the further upward movement of the handle will force the tooth of the dog into the notch. The dog will be positively locked between the wheel and the trigger block, the handle will be locked against further upward movement.

50 The rotary movement imparted to the index wheel by the dog will carry the wheel further than the movement given to it by the pawl. It will thus be seen that while the greater part of the movement of the index 55 wheel is imparted by the pawl, the final movement, and the locking of the wheel, are by means of the dog, and when the latter is in position in the notch, the wheel is positively locked against movement in either direction. By this means all tendency of the wheel to overthrow, or backlash is obviated.

When the revolving carriage is in the position just above described, the second of the receiving tubes is in position in alinement 65 with the loading tube, and the first receiving

tube containing five type has to be moved one step beyond said point of alinement to the position *y* Fig. 3, and the last type inserted therein as bearing against the straight portion of the inner face of the frame 1^a having passed the inclined portion 28. The gauge ring 38 is now moved up to engage the first type inserted in the tube and is secured in such position by means of the set screw 37.

The operation above described is now repeated until each of the receiving tubes has received five type, except that the operator is not obliged to count the type, but need simply push against the outermost type in the loading tube until the row of type can be moved no further. When the row cannot be moved further to the left, the handle is depressed and the carriage will be revolved step-by-step, until all of the tubes in the carriage has received five type.

85 The gauge ring is now released from the rod 3 and moved back away from the type. The feeding tube carrying the A's is removed by reversing the operation of placing it in position, and a tube containing B's is 90 substituted, and four type are counted out and moved into the first receiving tube as before. When the tube containing nine type has been moved to the position *y* the gauge ring is moved up and secured in position as 95 previously described.

When a considerable number of type are 100 in the receiving tubes there is some elasticity or slack in the rows, and the inclined face 28 is provided to take care of this contingency. The type cannot be moved into absolute contact by hand, and the incline 28, as shown in Fig. 3 will provide considerable leeway, and prevent the type from being injured as the carriage moves relatively to the 105 frame 1^a. As the carriage moves from the delivery position to the position *y* Fig. 3, the type are crowded into intimate contact, and the corners of the bodies will not be injured as would be the case if the incline 28 110 were not employed.

When the gauge ring 38 has been moved back until the hub 36 engages the foot of the lever 35, as shown at *i* Fig. 1, the tubes in the carriages will have received as many 115 type as each is designed to hold, and the last type will be flush with the right hand edge of the annulus 20 and bearing against the inner face of the frame member 1^a, it being understood that the annulus is in close 120 contact with the inner side of the member 1^a.

The lever 39 is now moved until the foot 40 is raised from the path of the hub 36, the screw 37 is loosened and the hub is moved back until it engages the ear 35, as 125 shown in broken lines at *j* Fig. 1. The ring 38 is now clear of the closed ends of the tubes, and the inner ends of the tubes are free of type.

Pressure is now applied to the last type in- 130

5 inserted in one of the tubes and all of the type in that tube are moved into the space at the left hand end of said tube, it being understood that distance between the position *i* of the ring 38 and the closed end of the tube *a* is greater than the width of the annulus 20 whereby the type will be moved to the left beyond the open end of the tube before the type first inserted therein reaches the closed 10 end of the tube. The tube may then be moved back against its block 11 to move the latter against the tension of its spring. This will free the open end of the tube from beneath the lips 22, and the spring 19 will 15 move the tube radially outward. The open end of the tube may now be raised and the partly closed end may be freed from the pin 12 and the notch 9 and a clip *f* placed over the open end of the tube and slid into 20 engagement with the last type inserted. The type are thus secured in the tube and the latter is now ready to be assembled with others into complete fonts.

During the removal of the tubes from the 25 carriage the dog 49 will be unlocked by disengagement of the trigger 53 therefrom, and the dog and pawl 47 may be lifted from engagement with the index wheel 41 by the cam 54. The carriage may now be rotated 30 by means of the hand wheel 43 to bring the tubes within convenient reach of the operator.

It is to be understood that the indexing device is capable of uses other than in connection with fonting apparatus without substantial change in the device.

In accordance with the provisions of the patent statutes, the invention has been described in connection with what is now considered to be the best embodiment thereof, but it is to be understood that the apparatus illustrated is merely illustrative, and that the invention may be carried out in other ways.

45 The invention having been described what is claimed as new and desired to be secured by Letters Patent of the United States, is—

1. An apparatus of the character described, comprising a delivery element 50 adapted to carry a plurality of bodies, a receiving element in axial alinement therewith, means whereby bodies may be transferred from the delivery element to the receiving element, and a gauge for regulating the 55 number of bodies delivered.

2. An apparatus of the character described, comprising a delivery element adapted to carry a plurality of bodies, a receiving element in axial alinement therewith, 60 means whereby bodies may be transferred from the delivery element to the receiving element, and a movable gauge for regulating the number of bodies delivered.

3. An apparatus of the character described, 65 comprising a delivery element adapted to

carry a plurality of bodies, a receiving element in axial alinement therewith, means whereby bodies may be transferred from the delivery element to the receiving element, a movable gauge for regulating the number of 70 bodies delivered, and means for locking the gauge in position.

4. An apparatus of the character described, comprising a delivery element adapted to 75 carry a plurality of bodies, a plurality of receiving elements in circular series, means for moving the receiving elements step-by-step to bring them successively into axial alinement with the delivery element, means for locking the receiving elements in position, means whereby bodies may be moved from the delivery element to the receiving 80 element in alinement therewith, and a gauge whereby the same number of bodies may be delivered to each receiving element. 85

5. An apparatus of the character described, comprising a delivery element adapted to carry a plurality of bodies, a plurality of receiving elements in circular series, means for moving the receiving elements step-by-step to bring them successively into axial alinement with the delivery element, 90 means for locking the receiving elements in position, means whereby bodies may be moved from the delivery element to the receiving element in alinement therewith, and a gauge cooperating with all of the receiving elements whereby the same number of bodies may be delivered to each receiving 95 element. 100

6. An apparatus of the character described, comprising a delivery element adapted to carry a plurality of bodies, a plurality of receiving elements in circular series, means for moving the receiving elements step-by-step to bring them successively into axial alinement with the delivery element, means for locking the receiving elements in position, means whereby bodies may be moved from the delivery element to the receiving 105 element in alinement therewith, and a movable gauge whereby the same number of bodies may be delivered to each receiving element. 110

7. An apparatus of the character described, comprising a delivery element adapted to carry a plurality of bodies, a plurality of receiving elements in circular series, means for moving the receiving elements step-by-step to bring them successively, into axial alinement with the delivery element, means for locking the receiving elements in position, means whereby bodies may be moved from the delivery element to the receiving element in alinement therewith, and a movable, annular gauge common 120 to all of the receiving elements whereby the same number of bodies may be delivered to each receiving element. 125

8. An apparatus of the character de- 130

- scribed, comprising a delivery element adapted to carry a plurality of bodies, a plurality of receiving elements in circular series, means for moving the receiving elements step-by-step to bring them successively into axial alinement with the delivery element, means for locking the receiving elements in position, means whereby bodies may be moved from the delivery element to the receiving element in alinement therewith, and a gauge surrounding the series of receiving elements whereby the same number of bodies may be delivered to each receiving element.
- 15 9. An apparatus of the character described, comprising a delivery element adapted to carry a plurality of bodies, a plurality of receiving elements in circular series, means for moving the receiving elements step-by-step to bring them successively into axial alinement with the delivery element, means for locking the receiving elements in position, means whereby bodies may be moved from the delivery element to the receiving element in alinement therewith, and a movable annular gauge surrounding the series of receiving elements whereby the same number of bodies may be delivered to each receiving element.
- 20 10. An apparatus of the character described, comprising of delivery element adapted to carry a plurality of bodies, a plurality of receiving elements in circular series, means for moving the receiving elements step-by-step to bring them successively into axial alinement with the delivery element, means for locking the receiving elements in position, means whereby bodies may be moved from the delivery element to the receiving element in alinement therewith, and a movable annular gauge surrounding the series of receiving elements whereby the same number of bodies may be delivered to each receiving element.
- 25 11. An apparatus of the character described, comprising a delivery element adapted to carry a plurality of bodies, a plurality of receiving elements in circular series, means for moving the receiving elements step-by-step to bring them successively into axial alinement with the delivery element, means for locking the receiving elements in position, means whereby bodies may be moved from the delivery element to the receiving element in alinement therewith, and a movable annular gauge surrounding the circular series of receiving elements, the said elements being free of the gauge, said gauge being in position to be engaged by the first body placed in each of such elements, means for adjusting the gauge longitudinally of the said elements, and means for locking the gauge in position.
- 30 12. An apparatus of the character described, comprising a shaft, opposed frames for supporting the shaft, discs secured to and spaced apart on the shaft, a series of spaced body receiving elements carried on the peripheries of the discs, there being an opening in alinement with each element through one disc, there being an opening through one frame member the same radial distance from the shaft as the receiving element openings, a delivery element adapted to carry bodies, said element being secured in alinement with the last mentioned opening, means for automatically giving the discs a step-by-step movement to bring the receiving elements successively into alinement with the delivery element, means for transferring bodies from the delivery element to the receiving element in alinement therewith, a gauge carried by the frame and movable longitudinally thereof to limit the number of bodies transferred from one element to the other, and means for moving the elements longitudinally of the apparatus to disengage the elements therefrom.
- 35 13. An apparatus of the character described, comprising a shaft, opposed frames for supporting the shaft, discs secured to and spaced apart on the shaft, a series of spaced body receiving elements carried on the peripheries of the discs, there being an opening in alinement with each element through one disc, there being an opening through one frame member the same radial distance from the shaft as the receiving element openings, a delivery element adapted to carry bodies and secured in alinement with the last mentioned opening, means for automatically giving the discs a step-by-step movement to bring the receiving elements successively into alinement with the delivery element, automatic means for locking the discs in position, means for transferring bodies from the delivery element to the receiving element in alinement therewith, means for unlocking the discs, a gauge carried by the frame and movable longitudinally thereof to limit the number of bodies transferred from one element to the other, and means for moving the elements longitudinally of the apparatus to disengage the elements therefrom.
- 40 14. An apparatus of the character described, comprising a rotary device having end walls and carrying a series of body receiving tubes, a frame for supporting such

device, one end of the rotary device being in close proximity to one frame member, a delivery tube adapted to carry a plurality of bodies carried by the said frame member, 5 there being means of communication through the frame member and device from the delivery tube to a receiving tube, means for rotating the device step-by-step to bring the receiving tubes successively into axial 10 alinement with the delivery tube whereby bodies may be transferred from the latter to the former through the frame member and a wall of the frame member at the point of transfer of 15 the bodies from said member to the wall of the device being inclined in the direction of travel of the device whereby the bodies will be crowded into the element by the rotation thereof, and a gauge against which the 20 bodies will be moved by the inclined portion.

15. An apparatus of the character described, comprising a rotary device having end walls and carrying a series of body receiving tubes, a frame for supporting such device, one end of the rotary device being in close proximity to one frame member, a delivery tube adapted to carry a plurality of bodies carried by the said frame member, 25 there being means of communication through the frame member and device from the delivery tube to a receiving tube, means for rotating the device step-by-step to bring the receiving tubes successively in axial alinement 30 with the delivery tube whereby bodies may be transferred from the latter to the former through the frame member and a wall of the device, the wall of the frame member at the point of transfer of the bodies from said 35 member to the wall of the device being inclined in the direction of travel of the device whereby the bodies will be crowded into the element by the rotation thereof, and an adjustable gauge against which the bodies will 40 be moved by the inclined portion.

16. An apparatus of the character described, comprising a frame having end members, a rotary device comprising discs carried on a shaft and spaced apart, a circular series of receiving tubes carried in notches in the peripheries of the discs, one 50 of said discs working in proximity to the inside of one of the frame members, there being a slot extending longitudinally of each tube and facing outward, there being 55 an opening in the disc communicating with each tube, there being an opening in the frame member in alinement with a disc opening, a delivery tube carried in the 60 frame opening, there being a longitudinal slot in said delivery tube, said tube carrying a plurality of bodies having oppositely disposed notches therein, the edges of the slot engaging the notches to support the

body, said body being otherwise unsupported, the said frame member and disc being slotted in radial alinement with the tubes carried thereby, there being a lip extending axially of the disc between each pair of tubes carried thereby, there being a space between 65 the lips, said space being in alinement with the tube slots and the disc slots, spring pressed means engaging the tubes with the under sides of the lips, similar lips engaging the delivery tube, and spring pressed 70 means engaging said tube with the lips, the lips, frame and disc being raised above the sides of the tubes, the outer surfaces of the lips being inclined away from the said disc and frame member.

17. An apparatus of the character described, comprising frame members spaced apart, a shaft journaled in the members, a pair of discs carried by the shaft and spaced apart, there being a series of peripheral notches in one disc, a series of blocks each held against one side of said disc by spring pressure, each block closing an end of a notch, a pin projecting from each block into a notch, a similar number of peripheral notches in the other disc, a saddle block in each of said latter notches, there being a semi-cylindrical groove in each saddle block, a spring tending to force each saddle block radially outward, a member carried by said disc and having a rim projecting over the saddle blocks, there being an opening in the member in alinement with the groove of each saddle block, there being a slot in the member communicating with each opening, 90 said slots extending through the rim, a series of longitudinally slotted tubes carried in alined notches, one end of each tube being engaged by a pin on a block of the first mentioned disc, the opposite end of each tube resting in the groove of a saddle block and being forced against the rim of the second mentioned disc by means of the saddle block spring, the slot of each tube being in alinement with a slot in the said disc, and an 95 alining disc carried by the shaft between the aforementioned discs and engaging the inner sides of the tubes.

18. An indexing device comprising a member adapted to be rotated step-by-step, a disc carried by the member, there being a series of notches in the periphery of the disc, a pivoted lever, a pawl carried by the lever and adapted to engage a notch in the disc, a spring moving the lever to rotate the disc 115 by engagement of the pawl therewith, and a stop for locking the disc against movement.

19. An indexing device comprising a frame, a member adapted to be rotated step-by-step, a disc carried by the member, there being a series of notches in the periphery of the disc, a pivoted lever, a pawl carried by the lever and adapted to engage a notch in

the disc, a spring for moving the lever to rotate the disc by engagement of the pawl, therewith, and a stop adapted to be engaged by an element on the lever for locking the 5 disc against movement.

20. An indexing device comprising a frame, a member adapted to be rotated step-by-step, a disc carried by the member, there being a series of notches in the periphery of 10 the disc, a pivoted lever, a pawl carried by the lever and adapted to engage a notch in the disc, a spring for moving the lever to rotate the disc by engagement of the pawl therewith and a stop adapted to be engaged 15 by a spring actuated trigger carried by the lever for locking the disc against movement.

21. An indexing device comprising a frame, a member mounted in the frame and adapted to be given a rotary, step-by-step 20 movement, a disc having spaced notches in its periphery, a lever pivoted on the axis of the member, a pawl carried by the lever and adapted to engage a notch, an element carried by the frame and adapted to engage 25 a notch, means for causing the element to engage the periphery of the disc, and means carried by the lever for engaging the element with a notch to rotate the disc.

22. An indexing device comprising a 30 frame, a member mounted in the frame and adapted to be given a rotary, step-by-step movement, a disc having spaced notches in its periphery, a lever pivoted on the axis of the member, a pawl carried by the lever and 35 adapted to engage a notch, an element having a tooth adapted to engage a notch, a spring for causing the element to engage the periphery of the disc, and spring actuated means carried by the lever for engaging the 40 tooth of the element with a notch to rotate the disc and to lock the element between the disc and lever.

23. An indexing device comprising a frame, a member mounted in the frame and 45 adapted to be given a rotary, step-by-step movement, a disc having spaced angular notches in its periphery, a lever pivoted on the axis of the member, a pawl carried by the lever and adapted to engage a notch, an 50 element pivoted to the frame, a spring for causing the element to engage the periphery of the disc, spring actuated means carried by the lever for engaging the tooth of the element with a notch to rotate the disc, and 55 to lock the element between the disc and lever, and means for locking the element out of engagement with the disc.

24. An indexing device comprising a frame, a member mounted in the frame and 60 adapted to be given a rotary step-by-step movement, a disc having spaced angular notches in its periphery, a lever pivoted on the axis of the member, a pawl carried by the lever and adapted to engage a notch, a spring 65 for moving the lever to rotate the disc by

the engagement of the pawl with a notch, an element pivoted to the frame, said element having an angular tooth adapted to engage a notch, a spring for causing the element to engage the periphery of the disc, 70 spring actuated means carried by the lever for engaging the tooth with a notch to rotate the disc, and to lock the element between the disc and lever, means for locking the element out of engagement with the disc, and means 75 carried by the element for disengaging the pawl from the disc.

25. An indexing device, comprising a member to be rotated step-by-step, there being a series of spaced notches in the member, 80 a lever pivoted relatively to the member, a pawl pivoted on the lever and adapted to engage the member whereby the latter will be rotated by a pivotal movement of the lever, a dog movable relatively to the member and the lever, said dog having a tooth adapted to accurately fit into a notch in the member, and means carried by the lever for engaging the tooth with a notch to further 85 rotate the member. 90

26. An indexing device, comprising a member to be rotated step-by-step, a disc carried by the member, there being a series of spaced angular notches in the periphery of the disc, a lever pivoted on the member, 95 a pawl pivoted on the lever, a spring for engaging the pawl with the periphery of the disc whereby the latter will be rotated by a pivotal movement of the lever, a dog movable relatively to the disc and the lever, said 100 dog having a tooth adapted to accurately fit into a notch in the disc, means carried by the lever for engaging the tooth with a notch to further rotate the disc and to lock the disc against movement in either direction. 105

27. An indexing device, comprising a member to be rotated step-by-step, a disc carried by the member, there being a series of spaced angular notches in the periphery of the disc, a lever pivoted on the member, 110 a pawl pivoted on the lever, a spring for engaging the pawl with the periphery of the disc whereby the latter will be rotated by a pivotal movement of the lever, a dog movable relatively to the disc and the lever, said 115 dog having a tooth adapted to accurately fit into a notch in the disc, means carried by the lever for engaging the tooth with a notch to further rotate the disc and to lock the disc against movement in either direction, and 120 means for locking the dog out of the path of movement of the disc.

This specification signed and witnessed this third day of June, 1921.
